UNITED STATES PATENT OFFICE.

JOHN RAE, OF PHILADELPHIA, PENNSYLVANIA, ASSIGNOR TO KEARNS MANUFACTURING COMPANY, OF PHILADELPHIA, PENNSYLVANIA, A CORPORATION OF DELAWARE.

DRESS-FORM.

991,241.

Specification of Letters Patent.

Patented May 2, 1911.

Application filed March 30, 1910. Serial No. 552,292.

To all whom it may concern:

Be it known that I, JOHN RAE, a citizen of the United States, residing at Philadelphia, county of Philadelphia, and State of Pennsylvania, have invented a new and useful Improvement in Dress-Forms, of which the following is a full, clear, and exact description, reference being had to the accompanying drawings, which form a part of this specification.

The object of my invention is to produce a dress form corresponding to that of a typical human figure from the neck to below the hips, which may be adjusted to lengthen and shorten the form, to contract and expand it at various points, and to vary its contour at any part thereof, either symmetrically or arbitrarily, to accommodate the form to all ordinary diversities of the human figure.

Another object of the invention is to separately effect any particular local adjustment without incidentally effecting any other local adjustment, whereby any part of the form may be adjusted independently.

Another object of the invention is to construct substantially the whole of the exterior skeleton of the form of material of maximum lightness, elasticity and pliability extending substantially throughout the length of the form, so as to preserve the continuity and smoothness of the form under all adjustments while enabling it to readily flex and bend under the influence of the adjusting mechanism.

The invention has for its more general object to produce a dress form excelling in the qualities of scope, flexibility, simplicity and durability.

The means whereby the above objects are effected may be understood by reference to the annexed drawings and the following general and particular description thereof, which illustrate a preferred embodiment of my invention.

In the drawings: Figure 1 is a front view of the dress form. Fig. 1^A is a detail plan view of a part of the shoulder and chest portion of the form. Fig. 2 is a side view, partly in section, of the form, with certain parts omitted. Fig. 3 is a detail sectional plan on the line 3—3 Fig. 2 of a part of the neck portion of the form. Fig. 4 is a detail end view of the shoulder portion of the form. Fig. 5 is a detail sectional view on

the line 5—5 Fig. 2 of the locking device for one of the skirt extenders. Fig. 6 is an enlarged plan view of the hip extenders connected with the exterior wire skeleton and of the means for spacing the contour wires and shaping the form at the hip. Figs. 7 and 8 are detail views of parts of Fig. 6. Fig. 9 is an elevation showing the central post and the devices for vertically adjusting the extenders. Fig. 10 is a detail view of parts of one of said devices. Fig. 11 is a section on line 11—11; Fig. 10. Fig. 12 is a detail view of the means for locking the post to the tubular portion of the standard. Fig. 13 is a detail view of the one of the devices for adjusting the arm hole members back and forth and locking in the adjusted position. Fig. 14 is a detail sectional view of one of the devices for adjusting the shoulder part of the form in and out and locking it in its adjusted position. Fig. 15 is a diagrammatic view illustrating the principle of operation common to certain of the adjusting or locking devices. Figs. 16 and 17 are detail views of the means for locking the portable base 80 to the floor.

The main body of the dress form comprises an exterior wire skeleton composed of three series of vertically extending elastic contour wires 1, 2 and 3. The contour wires 1, which are relatively thick and comparatively inelastic, each extend from the hip portion of the form to the lower end thereof, where it is bent upon itself and extends upward to the hip portion. These wires constitute the skirt portion of the form. The contour wires 2, which are relatively thinner and more elastic, extend from the waist portion of the form down to below the hip portion, and at their lower ends are bent to form eyes that engage the wires 1. This construction permits the lower ends of the wires 2 to slide along the wires 1. The contour wires 3, which are also relatively thin and elastic, extend from the neck and shoulder portions of the skeleton down to below the hip portion but above the lower termini of the wires 2, and, like wires 2, are provided at their lower ends with eyes embracing the wires 1.

The wires 1, 2 and 3, are attached, at points corresponding to the shoulder, bust, waist and hip portions of the form, to extenders connected with the upright central internal support, which extenders are adapt-

ed for adjustment vertically, radially and angularly, as hereinafter described. The division of the contour wires into three series, arranged as described, possesses important advantages in that it increases the range of adjustment and flexibility and in particular permits different parts of the form to be adjusted with a greater degree of independence than is possible in a structure 10 wherein the contour wires extend the entire length of the figure besides enabling the relatively sharp change of direction at the waist to be secured without bending any of the wires at a relatively sharp angle, each 15 series of wires 2 and 3, on the contrary, at all points and in all possible adjustment of the form, being curved on a relatively long radius, while the skirt portion, where no pronounced curvature is necessary and 20 where comparative rigidity is desirable, may be made of less flexible material. The wires 2 and 3 are preferably of about .04" diameter, and all the wires are of sufficient elasticity to enable them to yield to effect the 25 variations in contour dictated by the adjusting mechanism to which they are respectively secured. At the same time, all the contour wires are of sufficient rigidity to cause them to hold the "set" effected by the 30 adjusting devices, so that they may be readily locked in any position to which they may be moved or flexed.

4 is the portable base and 5 a tube extending upward therefrom, said base and tube 35 forming a standard on which the dress form is supported.

6 is a post inserted in the tube 5 and extending within, and nearly to the top of, the skeleton, and supporting the same as 40 hereinafter described.

7 is a frame (see Fig. 12) secured to the tube 5 and extending above the upper end thereof and surrounding the tube and post.

8 is a lever fulcrumed on the frame 7 at 45 9 and having an orifice through which the post 6 extends.

10 is a spring surrounding the post and confined between the top of the frame 7 and the lever 8 and normally holding the lever 50 in the inclined position shown.

The orifice in the lever 8 is of slightly greater diameter than the post 6 (see diagram, Fig. 15), but when the lever assumes the normally in-lined position described, opposite edges of the orifice engage the post and prevent any downward movement of the same. The lever 8 is connected, by a rod 11, with a foot-lever 12 sleeved loosely on the tube 5 and fulcrumed upon a collar 13 secured to the tube 5. By depressing the lever 12, the lever 8 is rocked on its fulcrum toward a position at a right angle with the axis of the tube 5 and post 6, thereby freeing the post from the bite of the lever 8, 65 permitting the operator to lower the post

until the form is adjusted to the proper height. The operator then releases the lever 12 and the spring 10 immediately returns the lever to its normal gripping position. The lever 8 at no time prevents the 70 operator from raising the post and when so raised, the lever 8 automatically engages and prevents its lowering.

To prevent the post 6 from being wholly withdrawn from the tube 5, a segment-shaped section of the lower end of the post is cut away (see Fig. 9) and the lower end of a leaf spring 14 is riveted to the post in the lower end of its cut-away portion. The upper end of the spring 14 curves outward 80 as shown. When the post is inserted into the tube, the upper corners of the leaf spring are engaged by the tube walls and forced in. If it be attempted to withdraw the post, the upper end of the spring 14 will spring out 85 as soon as it emerges from the tube and immediately thereafter will engage the lever 8, which will prevent further movement of the post.

Mounted on the post so as to slide and 90 swing thereon are a series of members which may be designated respectively as the skirt, hip, waist and bust-extenders *a*, *b*, *c* and *d*. Each of the members *b*, *c* and *d* is vertically adjustable relatively to the post 6 and to the 95 remaining members. Each member comprises a plate and radial extenders properly mounted thereon and connected with the exterior skeleton.

The means for vertically adjusting and 100 supporting the hip extender *b* will first be described (see Figs. 1, 2, 9, 10 and 11).

The plate 20 of the hip extender is connected, by means of vertically extending rods 21, with an adjuster *e* comprising a pair 105 of plates 22, 22, having collars 23, 23, slideable on the post 6; the rods 21 extending through both plates 22, 22 and held from movement relatively thereto by cross-pins 21'.

24, represent a pair of levers sleeved on the post 6 between the two collars 23, 23. These levers are fulcrumed, at one side of the post 6, respectively above and below a plate 25 supported between side pieces 26, 26 connecting the plates 22, 22. The ends of the levers 24, 24, on the opposite side of the post, are sleeved on a pin 27 connecting the plates 22, 22. Between each lever 24 and its most adjacent plate 22, is a washer 28, loose 120 on the pin, and a coil spring 29, surrounding the pin and confined between the plate and the washer. The orifices in the levers 24, 24, are of slightly greater diameters than the post 6, but when, under the influence of the 125 springs 29, 29, the levers assume the normally inclined position shown, opposite edges of the orifices engage the post and prevent any vertical movement of the plates 22, 22, thereon, whereby the plate 20 of the hip- 130

extender, is automatically held in any position to which it has been adjusted. If it is desired to raise or lower the hip-extender, the ends of the levers 24, 24, beyond their 5 fulcrums are pressed toward each other, thereby freeing the post from the grip of the levers and permitting the latter, together with the plates 22, 22 and the plate 20, to be moved either up or down to the position to 10 which it is desired to adjust the extender. This accomplished, the levers 24, 24, are released, and their respective springs 29, 29, act immediately to return the levers to their 15 normally inclined positions, thereby automatically locking the plate 20 in its newly adjusted position.

The means for vertically adjusting the supporting plate 30 of the waist-extender *c* and the means for vertically adjusting the 20 supporting plate 40 of the bust-extender *d*, are each the same as the means just described for vertically adjusting the supporting plate 20 of the hip extender.

f represents the adjuster for the waist- 25 extender *c*, being connected therewith by means of the vertically-extending rods 31.

g represents the adjuster for the bust- 30 extender *d*, being connected therewith by means of the vertically extending rods 41.

35 The pair of plates 32, 32 of the adjuster *f* and the pair of plates 42, 42 of the adjuster *g* are provided with orifices to permit the rods 21 to extend loosely through them, said orifices at the same time guiding the rods 21 in their vertical movement.

The pair of plates 42, 42 of the adjuster *g* and the plate 20 of the extender *b* are provided with similar orifices to accommodate and guide the rods 31.

40 The rods 41 extend through orifices in the plate 30 of the extender *c* in the plate 20 of the extender *b*, in the plates 32, 32, of the adjuster *f*, in the plates 22, 22 of the adjuster *e*, and in the plate 50 of the skirt extender *a*. The lower ends of the rods 41 extend into, and are adapted to slide or telescope within guides in guide bars 43, 43. These guide bars are in turn adapted to slide through orifices in plates 44 and 45 secured to

50 the frame 7. In lowering the post 6 with the form supported thereon from its uppermost position, the guide bars 43 move with the rods 41 until the former contact with the base, 4, see Fig. 1, after which the rods 41 55 slide from the top to the bottom of the guides in the bars 43. In raising the post 6, the opposite order of movement takes place. This arrangement permits a longer range of travel for skirt length than would otherwise be possible, consistent with the proper guidance of the rods 41 throughout their movement.

The construction of the skirt extender *a* will now be described (see Figs. 2 and 5).

65 Secured to the plate 50 of the skirt ad-

juster is a plurality of metal strips 51. These strips are preferably four in number and radiate from the central post 6 toward the front, the back and both sides of the form. Each strip extends beneath the plate 70 50, and is secured thereto, its inner end being bent upward through the plate, while its outer end is bent successively upward above the level of the plate, outward and downward.

75 52 are rods, equal in number to the strips 51, and, like them, radiating from the post 6. The rods 52 extend through orifices in the vertical bends of the strips 51 and extend a considerable distance beyond the ends of the strip 51 and almost to the exterior skeleton, to which they are attached by means hereinafter described. Surrounding each

80 rod 52, between the two outer vertical bends of the strip 51, is a block 53, to which is secured a threaded bolt 54, extending up through the strip. Threaded on the bolt 54 is a thumb-nut 55 engaging the strip. By

85 turning the nut 55 in one direction, the bolt 54 and block 53 may be drawn up a short 90 distance thereby flexing or bending the rod 52 and holding it from lateral movement. By turning the nut 55 in the opposite direction, the rod 52 is straightened, permitting it to be adjusted laterally. By suitably ad-

95 justing the different rods 52, the diameter and shape of the skirt portion of the skeleton may be varied as desired. The method of connecting the rods 52 of the skirt extender to the contour wires 1 is the same as that 100

hereinafter described for connecting the hip, waist and bust-extenders to their corresponding contour wires.

The construction of the hip adjuster *b* will now be described (see Figs. 2, 6 and 7). 105

Secured to the plate 20 are four yokes 60, each formed from a thin strip bent to shape. Two of these yokes extend upward from the plate 20 and the other two extend downward therefrom.

110 61, 61, represent a pair of pins, one pair for each yoke, secured at one end to the plate and at the other end to the connecting member of the yoke.

62 is a bar extending loosely through the vertical members of the yoke and through a guide piece 63 on the plate 20, said bar being adapted to slide longitudinally of the plate 20 and be guided in such movement by the yoke 60 and the piece 63.

115 64 is a toothed lever, pivoted at its inner end on the inner end of the bar 62 and extending through slots in the vertical members of the yoke.

65, 65, are springs coiled about the pins 120 61, 61, and confined between the plate 20 and the washer 66 sleeved on the pins and bearing against the lever 64. Under the influence of these springs, the toothed edge of the lever 64 is held engaged with one of the 125

130

vertical members of the yoke 60 through which the lever extends. On the outer end of the bar 62 is a plate 67 which is slotted to receive the outer end of the lever 64, and which is connected with the connecting member of a yoke 68 of a holder *k*. One arm of the yoke 68 is provided with two orifices through one of which extends one of the contour wires 1 (which is bent upon the yoke and thereby secured in fixed relation thereto), and through the other of which loosely extends one of the contour wires 2.

69 is a finger piece secured near the outer end of the lever 64. By depressing the finger piece 69, the lever 64 is moved on its pivot toward the plate 20, thereby compressing the springs 65 and freeing the toothed edge of the lever from engagement with the yoke 60 permitting the lever 64, and with it the bar 62, to be moved radially with respect to the post 6, thereby moving in or out the contour wires connected with the bar 62. When the contour wires have been adjusted to their desired positions, the pressure on the finger piece 69 is released, and the springs 65 act to reengage the lever 64 with the yoke 60.

The waist extender *c* and the bust extender *d* are constructed like the hip extender *b*. The yokes 68 of the waist extender are, however, connected fixedly with contour wires 2 and loosely with contour wires 3; while the bust extender is connected (loosely) with only contour wires 3. The rods 52 of the skirt extender also carry holders *k*, which engage contour wires 1.

In order to maintain the contour wires at uniform distances apart, the following means are provided (see Figs. 1, 6, 7 and 8.) Each holder *k* is provided with laterally extending ears 70. 71 represent sets of lazy tongs, there being one set between the ears 70 of adjacent holders *k* of each extender. Secured to pivot pins of each set of lazy tongs are holders 72, engaging the contour wires. By means of this construction, an inward or outward movement of any one of the contour wires, causes all the contour wires within the quadrant containing the one directly operated to approach or recede from adjacent wires to a uniform degree. The foregoing means for uniformly spacing apart the contour wires do not, however, necessarily insure any uniformity in the degree to which the various contour wires are moved radially. Further, it is not always desirable for all the contour wires to be moved outwardly or inwardly to precisely the same extent, as cross-sections through different human bodies will exhibit as wide diversities in shape as in size. To provide for adapting the contour wires to any given shape, the following means are provided

(see Figs. 1, 6, 7 and 8). Extending through the arms of each yoke 68 of each of the extender holders *k* is a bolt 74, on the upper end of which is threaded a thumb nut 75 engaging the upper arm of the yoke. The bolt between the arms of the yoke, is slotted vertically and through this slot extend two thin flat steel tapes 76. The end of one of the tapes, 76, is bent down against the bolt so as to hold it in fixed relation thereto. This tape extends through guiding flanges on successive holders 72 until it reaches the next holder *k*, through the slotted bolt of which it extends freely for an adjusting length. To this bolt is attached another tape 76, which in like manner extends on around another quarter of the contour. Thus there are four tapes, or tape sections, for each extender, each being secured at one end to one extender member and in sliding engagement with the next adjacent extender member. These tapes can be flexed into any desired shape. If they are pulled in one direction, the curve between adjacent extender members is flattened, while if they are pushed in the other direction, the curve between adjacent extender members may be bulged out as far as desired. After the tape is manipulated to effect the desired curvature, its sliding end is held from longitudinal movement by turning the nut 75, drawing up the bolt 74 until the tape is confined against the upper arm of the yoke. The tape 76 is preferably slightly narrower, at its fastened end, than at its sliding end, so as not to obstruct the upward movement of the bolt 74 or prevent it binding the loose tape with a sufficient degree of tightness.

Secured to the plate 50 of the skirt extenders *a* are four upright rods 81 (see Figs. 2, 6 and 9) which extend up through orifices in the plates 20, 30, and 40 of the hip, waist and bust extenders respectively. The upper ends of the rod 81 are connected by a plate 82 having a sleeve held by a set-screw on the post 6. The skirt extender is thus hung in fixed relation from the plate 82. The rods 41 connected with the bust extender extend upwardly therefrom and slide through orifices in the plate 82 thereby keeping the various extender plates in alinement. Secured to the sleeve of the plate 82 is the plate 80 of a chest extender *h*. On this plate are mounted two extender contrivances similar in construction to the four extender contrivances mounted on each of the plates 20, 30, and 40, and similarly lettered. These two contrivances extend respectively forward and rearward and the holders *k* carried on the outer ends thereof, have orifices through which loosely extend the contour wires 3.

The means for shaping the shoulder portion of the form will now be described (see Figs. 1, 1^A, 2 and 4.)

Secured to the plate 80 of the chest-extender *h* is a frame 83, through which the cross-rod 84, 85, extend from shoulder to shoulder. Near the outer ends of the rods 84, 85, are sleeved the shoulder plates 86, 86. Each plate 86 is capable of moving along the rods 84, 85, to narrow or widen the shoulder. To move said plate 86 along the rods and hold it in the position to which it may be adjusted the following means are provided. Secured to the plate is a frame, one arm 87 of which is sleeved on the rod 85 (see Fig. 14). 88 is a pin connecting the plate 86 and arm 87. 89, 89, are levers sleeved between their ends on the rod 85, each having an orifice slightly greater in diameter than the diameter of the rod 85. 90 is a spring coiled about the rod 85 and confined between the levers. Corresponding ends of the levers 89 are loosely sleeved on the pin 88, and bear against the washers 91, 91 on said pin. The spring 90 normally holds the levers 89 in the inclined position shown, in which position opposite walls of the orifice in each lever bite the rod 85 and hold the plate 86 from longitudinal movement thereon. When, however, the outer free ends of the levers 89 are moved toward each other, the grasp of the levers upon the rod 85 is released and the plate 86 can be moved longitudinally on the rods 84 and 85, thereby permitting each shoulder portion of the frame to be narrowed or widened. Each plate 86 also carries a frame 92, in guides wherein the rods 93 and 94 may be longitudinally moved. The forwardly extending rod 93 carries an ear 95. A set of lazy tongs 71 connect the ear 95 with one of the ears 70 on the holder *k* of the front member of the chest extender *h*. By moving forwardly or rearwardly the rod 93 at either shoulder, the size of the arm hole may be varied, while the lazy tongs (to the pivot pins of which the contour wires 3 are connected, by means of holders 72, as hereinbefore described in the description of the hip extender) maintain the contour wires 3 at uniform distances apart. By similar means the rearwardly extending rods 94 are connected with the rear member of the chest extender *h*.

The rods 93 and 94 are held in any position to which they may be adjusted on the frame 92 by two pairs of levers 96, 96 (see Fig. 13), which are loosely sleeved on the rods 93 and 94 respectively and are fulcrumed on pins 97, 97, on the frame 92 and are held in an inclined locking position by means of coil springs 98, 98, on the rods 93 and 94 respectively. By pressing together the outer ends of a pair of levers 96, the same are moved toward a position at right angles to their corresponding rod 93 or 94, thereby freeing the rod from the grasp of the levers and permitting the rod to be adjusted. After

adjustment, the levers are released and their actuating spring moves them into the position shown, in which position the rod is locked in its adjusted position.

Each forwardly extending rod 93 also carries one end of a tape 101, which extends through the holders 72 of the adjacent set of lazy tongs connecting such rod 93 and the front member of the chest extender *h*. The loose ends of each tape 101 are adjustably connected with the holder *k* on the outer front end of the chest extender. Similar tapes connect the rearwardly extending rods 94 with the rear member of the chest extender *h*.

The neck-forming device, the means for supporting it, for varying its diameter, and for raising and lowering it with respect to the body portion of the form, are constructed and operated as follows (see Figs. 1, 2 and 3). 110 is a post connected at its lower end with the rod 84. 111 is a flange on the post on which rests the coil spring 112 surrounding the post. 113 is a frame surrounding the post and resting on the coil spring 112. 114, 114, are channel bars depending from the frame. 115, 115, are guides riveted to the frame 83 on either side of the post 110 and having outwardly extending arms extending into the channel bars 114, 114. These guides prevent the neck forming device from tilting or turning, while permitting it to be moved up and down and guiding it in such movement. On the upper part of the frame 113 rest the inner ends of arms 116. The outer ends of arms 116 are secured to four neck-sections 117 whose lower ends rest upon the lower part of the frame 113. Secured to the inner ends of the arms 116 are pins 118 which project above the arms and engage curved cam slots 119 in a disk 120. Secured to this disk is a sleeve 121, which surrounds a threaded stem 100 and upper end of the post 110 and has secured to it an arm 122. The arm 122 is intended to be grasped and turned by hand, and when by this means the disk 120 is turned, the pins 118 engaging the slots 119 will be moved radially inward or outward, thereby imparting a similar movement to the neck-sections 117, 115 thereby expanding or contracting the neck portion.

The stem 100 screws into a longitudinal threaded hole on the post 110 and at its upper end has a head in the form of a knurled disk 123 for operating it by hand. By turning the knurled head in one direction, the sleeve 121 and the entire neck portion connected therewith are depressed against the pressure of the spring 112. By turning the knurled head in the opposite direction, the spring 112 acts to lift the neck portion. There is a pin cushion 102 attached to the

knurled head for the convenience of the operator.

Secured to each shoulder plate 86 is a nut 130, which carries a screw 131 having a head by which it may be turned. Ears 132 are swiveled in the head of the screw. To these ears are pivoted the outer end of a shoulder bar 133. The inner ends of the shoulder bars 133, 133, extend loosely through orifices in opposite neck sections 117, and it will be understood that as these neck sections are raised and lowered, as just described, the inner ends of the bars 133, 133, will be correspondingly raised and lowered, varying the slope of the shoulder. The outer ends of the bars 133, 133, are raised and lowered by turning the screws 131, taking care of unequal height of shoulders.

It is convenient to mount the portable base 4 on casters to permit it to be readily moved over the floor, but when in actual use it is desirable that it should remain stationary. The following construction permits of the mounting of the base on casters while enabling it to be frictionally locked to the floor whenever desired (see Figs. 16 and 17). Through one leg, or each of two or more legs, of the base extends a post 140, upon which is swiveled a bracket 141 carrying a caster 142. Upon the lower end of the post is threaded a nut 143 and a rubber block 144, the latter projecting below the post and provided with a conical centrally-located aperture 145 in its lower face. Mounted on the top of the leg is a frame or casing 146, orificed to permit the post 140 to extend through it. 147 is a spring confined between the top of the casing and a head 148 on the upper end of the post. 149 and 150 are pins extending through the casing and the leg on opposite sides of the post. 151 is a lever, fulcrumed at one end against the wall of an orifice in one side of the casing, loosely sleeved on the post 140 and the two pins 149 and 150, and at its other end projecting through another and larger orifice in the other side of the casing. 152 is a spring surrounding one of the pins and confined between the bottom of the casing and a washer on the casing beneath the lever 151. The diameter of the orifice in the lever through which the post 140 extends is slightly greater than the diameter of the post. The spring 152 normally holds the lever 151 in an inclined position, so that opposite edges of the orifice engage the post and hold the latter from upward movement. The lever, however, offers no resistance to downward movement of the post, as such downward movement moves the lever toward a horizontal position, thereby relieving its grip upon the post.

When the post is in its upper position, as indicated in Fig. 16, the rubber block 144

is above the level of the floor, and the dress form may be freely moved about on its casters. By bearing with the foot upon the head of the post 140, the latter may be depressed until the block 144 firmly engages the floor.

Upon releasing the foot pressure upon the post, the lever 151 immediately locks the post from rising in the base; and the compressed rubber block 144, partially relieved, expands and takes the weight off of the caster, this weight making sufficient friction between rubber block and floor to give the necessary resistance to lateral motion. The dress form is thus frictionally locked to the floor. To release the same, the outer upturned end of the lever 151 is depressed, thereby releasing its grip upon the post 140, and the latter, under the impulse of the spring 147, is immediately lifted.

The invention is not limited to the precise details of construction and arrangement shown, as various modifications thereof may be made without departing from the essential features of my invention. Nor is it intended to limit the application of certain specific features of novelty to the precise location to which said features are applied nor to the precise means described for embodying said features in practically operative form. For example, the devices comprising orifices, levers or plates sleeved on rods and adapted to effect adjustments by varying the angle thereof to the rods are shown in a number of different forms having different modes of operation; and such devices might be embodied in still other forms, or certain embodiments thereof embodying specific novelty might be applied to other portions of the form, without departing from this feature of my invention as expressed in the broader claims therefor.

While the contour wires are spoken of as "wires", they need not necessarily be wires in the strict sense of being circular cross-section, so long as they have sufficient pliability to adapt them for the purpose; although it is decidedly preferable to employ wires in the strict sense of the term, and many of the leading features of the form are arranged with a view to their utilization in substitution for plates of a rigid or semi-rigid character.

While the drawings illustrate a form corresponding to that of a portion of a typical woman's figure, it will be understood that the invention may be equally embodied in forms corresponding to the typical masculine figure when it is desired to employ the same for fitting garments.

Having now fully described my invention, what I claim and desire to protect by Letters Patent is:

1. A dress form comprising an exterior skeleton composed of vertically extending

contour wires divided into three series, one of which extends from the hip portion to the lower end of the form, the other of which extends from the waist portion to below the 5 hip portion, and the third of which extends from the upper portion of the form to below the hip portion.

2. A dress form comprising an exterior skeleton composed of vertically extending 10 contour wires divided into three series, one of which constitutes the skirt portion of the form, the second of which curves outward and downward from the waist portion and slidably engages the skirt wires, and the 15 third of which curves downward from the upper portion of the form successively convexly and concavely and also slidably engages the skirt wires.

3. In a dress form, the combination with 20 an internal post, of a hip extender supported thereupon, a series of external contour wires depending from the hip extender, a waist extender supported from said post, a second series of external contour wires depending from the waist extender and extending below the hip extender, extenders supported from said post above the waist extender, and a third series of external contour wires engaging the last named exten- 25 sors and extending below the waist extender.

4. In a dress form, the combination with 30 an internal post, of skirt-, hip-, waist-, bust-, and chest-extenders, and shoulder bars and neck member, all carried by said post, a series of external contour wires carried by the hip- and skirt-extenders, a second series of external contour wires carried by the waist- and hip-extenders, and a third series of external contour wires engaging the neck-member, 35 shoulder bars, and chest-, bust- and waist-extenders, the contour wires of each series being slidably engaged with the contour wires of another series.

5. In a dress form, the combination with 45 an internal post, of a series of devices independently adjustable on said post, means to hold said devices in their adjusted positions, rods extending upward from each device, a radially adjustable extender mounted on the 50 rods supported by each device, and external contour wires engaging the extenders.

6. In a dress form, the combination with 55 an internal post, of a series of devices independently adjustable on said post, means to hold said devices in their adjusted positions, rods extending upward from each device, a plate mounted on the rods supported by each device, radially extensible members supported on each plate, and external contour wires engaging said extensible members.

7. In a dress form, the combination, with 65 an internal post, of a series of adjusters independently adjustable on said post, a series of extenders above said adjusters, upright

rods connecting the several adjusters with their respective extenders, and external contour wires engaging the extenders.

8. In a dress form, the combination with 70 an internal post, of a series of adjusters slideable upon said post, each adjuster comprising a pair of plates and means to lock the same in fixed relation with the post, upright rods carried by the several adjusters and extending through and guided by the plates of 75 other adjusters, extenders above said adjusters, and supported on the rods carried by their respective adjusters, and external contour wires engaging the extenders.

9. In a dress form, the combination with 80 an internal post, of a series of adjusters slideable upon said post, each adjuster comprising a pair of plates and means to lock the same in fixed relation with the post, a corresponding series of extenders above said adjusters, each extender comprising a plate and radially adjustable members supported thereon, upright rods supported on the plates of each adjuster and connected with the corresponding extender and extending 85 through and guided by the plates between such adjuster and extender, and external contour wires engaging the extenders.

10. In a dress form, the combination with 90 an internal post and an external wire skeleton, of a hip extender within and engaging the skeleton, a waist-extender within and engaging the skeleton and located above the hip-extender, a bust extender within and engaging the skeleton and located above the 95 waist extender, a bust adjuster below the hip extender, a waist-adjuster below the bust-adjuster, a hip-adjuster below the waist adjuster, each adjuster comprising a member 100 slideable on the post, and means for locking said member to the post, and means carried by each adjuster connected with, and supporting, its corresponding extender.

11. In a dress form, the combination with 105 an internal post and an external wire skeleton, of devices for adjusting said wires vertically and circumferentially, said devices located within the skeleton and supported on the post and including plates and vertically extending supporting rods extending therethrough and guided thereby, vertically extending guide bars upon which certain of said rods are slideable, and means supported from the post and upon which said guide bars are vertically movable.

12. In a dress form, the combination with 110 a post and an external wire skeleton, of a pair of plates, collars and a frame slideable on the post, a pair of levers fulcrumed on the frame and having orifices through which the post extends, said orifices being of slightly greater diameter than the diameter of the post, springs normally holding said levers in an inclined position, whereby the 115 opposite walls of the orifices grip the post,

- rods extending upward from said plates, and an extender supported on said rods and connected with the skeleton.
13. In a dress form, the combination with 5 an external wire skeleton, of an internal support, a bar slideable radially relatively to the support and connected with said skeleton, a spring-pressed lever pivoted on said bar, and means adapted to lock said lever 10 when actuated by said spring.
14. In a dress form, the combination with an external wire skeleton, of an internal support, a bar slideable radially relatively to the support and connected with said skeleton, a 15 yoke carried on said support, a lever pivoted on said bar and having teeth adapted to engage said yoke, and a spring normally pressing said lever in engagement with said yoke.
16. In a dress form, the combination with 20 an external wire skeleton, of an internal post, a plate vertically movable on said post, a bar slideable radially in guides on said plate and connected with said skeleton, a spring 25 pressed lever pivoted on said bar, and means carried by the plate adapted to engage and lock said lever under the normal action of the spring, thereby holding the bar in its adjusted position.
17. In a dress form, the combination with 30 vertically extending contour wires of an external skeleton, of an internal support, a series of radially extensible devices mounted on said support, a set of lazy tongs connecting 35 each two adjacent extensible devices, and holders connected with the pivot pins of the lazy tongs and engaging said contour wires.
18. In a dress form, the combination with 40 vertically extending contour wires of an external skeleton, of an internal support, a series of radially extensible devices mounted on said support, holders engaging said contour wires and supported on said extensible 45 devices, flexible and non-elastic tapes each fixedly connected with one of said holders and slidably connected with other of said holders, and means to lock each tape in fixed relation to one of the holders in which it is 50 slideable.
19. In a dress form, the combination with 55 vertically extending contour wires of an external skeleton, of an internal support, a series of radially extensible devices mounted on said support, a set of lazy tongs connecting each two adjacent extensible devices, 60 holders engaging the contour wires and connected with the extensible devices and the pivot pins of the lazy tongs, and flexible and non-elastic tapes connecting the holders.
20. In a dress form, the combination with 65 vertically extending contour wires of an external skeleton, of an internal support, a series of radially extensible devices mounted on said support, a set of lazy tongs connect- ing each two adjacent extensible devices, 70 holders engaging the contour wires and connected with the extensible devices and the pivot pins of the lazy tongs, and flexible and non-elastic tapes, each fixedly connected at 75 one end with one of the holders connected with one of the extensible devices and extending loosely through successive holders carried by one adjacent set of lazy tongs and slidably engaging the holder carried by the 80 other extensible device to which said set of lazy tongs is connected, and means to lock said tape in fixed relation to the last named holder.
21. In a dress form, the combination with 85 vertically extending contour wires of an external skeleton, of an internal support, a series of radially extensible devices mounted on said support, holders each comprising a yoke supported on the outer end of each extensible device and engaging one of the contour wires and a pin extending through 90 said yoke, said pin being slotted between the arms of the yoke, a flexible and non-elastic tape extending through and slidable within 95 said slot and extending to the holder on the next adjacent extensible device, and a nut threaded on the end of the pin projecting beyond one arm of the yoke, whereby the turning of said nut confines said tape between one end wall of the slot and one arm of the yoke.
22. In a dress form, the combination with 100 vertically extending contour wires of an external skeleton, of an internal support, a series of radially extensible devices mounted on said support, holders each comprising a yoke supported on the outer end of each extensible device and engaging one of the contour wires and a pin extending through 105 said yoke, said pin being slotted between the arms of the yoke, a flexible and non-elastic tape extending through and slidable within 110 said slot and extending to and secured to the holder on one of the next adjacent extensible devices, a flexible non-elastic tape extending through said slot and held in fixed relation to said pin and extending to and slidably engaging the other next adjacent extensible device, and a nut threaded 115 on the end of the pin projecting beyond one arm of the yoke.
23. In a dress form, the combination with 120 an external wire skeleton, of an internal support, a strip secured thereto, a rod slideable laterally on said strip and connected with the external skeleton, a block between oppositely bent sections of the strip and through which said rod extends, a pin on 125 said block, and a nut threaded on the pin and engaging said strip, whereby the block may be moved to flex said rod and hold it in adjusted position.
24. In a dress form, the combination with 130 an internal post, of a frame supported there-

from, a pair of bars extending through said frame from one side to the other of the form, shoulder plates slidable on said bars, a neck forming contrivance supported on said frame, means to raise and lower the neck forming contrivance, a screw engaging each shoulder plate, a bar pivotally connected with the screw and loosely connected to the neck forming contrivance so as to be movable up and down with the latter.

24. In a dress form, the combination with a neck-forming contrivance and a shoulder plate, of means permitting the adjustment of said plate in and out and adapted to lock said plate in its adjusted positions, means to raise and lower the neck-forming contrivance, and a bar vertically adjustable and pivotally movable upon the shoulder plate and slidably engaging the neck forming contrivance.

25. In a dress form, the combination with

an internal post, of a shoulder plate, means by which the shoulder plate is supported from the post, adjustable means adapted to lock said plate at different distances from said post, a rod supported on the shoulder plate, means by which said rod may be moved back and forth on said plate, a chest extender supported from said post, a set of lazy tongs connecting said rod and chest extender, a flexible, non-elastic tape secured at one end to said rod and slidably engaging the chest extender, and means on the chest extender to secure said tape in fixed relation thereto.

In testimony of which invention, I have hereunto set my hand, at Philadelphia, on this 25th day of March, 1910.

JOHN RAE.
